(57) **CLAIM**

The ornamental design for footwear, as shown and described.

DESCRIPTION

FIG. 1 is a front perspective view of a shoe showing my
footwear design;

FIG. 2 is a left side view of the footwear shown in FIG. 1;
FIG. 3 is a right side view of the footwear shown in FIG. 1;
FIG. 4 is a front view of the footwear shown in FIG. 1;
FIG. 5 is a rear view of the footwear shown in FIG. 1; and,
FIG. 6 is a top view of the footwear shown in FIG. 1.
The broken line showing of the sole, heel cap, and buckle
assembly in relevant drawings shows unclaimed subject matter
for the design in those drawings.
